Inventor

Franklin P. Morrison,

UNITED STATES PATENT OFFICE.

FRANKLIN PHILIP MORRISON, OF BIG SKIN CREEK, WEST VIRGINIA.

BOX-LIFTER.

SPECIFICATION forming part of Letters Patent No. 423,621, dated March 18, 1890.

Application filed October 31, 1889. Serial No. 328,751. (No model.)

To all whom it may concern:

Be it known that I, FRANKLIN PHILIP MORRISON, a citizen of the United States, residing at Big Skin Creek, in the county of Lewis 5 and State of West Virginia, have invented a new and useful Box Lifter and Elevator, of which the following is a specification.

The object of this invention is to provide a convenient means for elevating or lowering 10 boxes from shelves above the heads of salesmen in stores, whereby access to the same may be had without the use of step-ladders or climbing upon the part of the salesmen.

With these general objects in view the invention primarily consists in a socket, preferably formed of sheet metal, secured to the exposed side or end of the box, said socket being of such shape as to adapt the same to receive and snugly fit the end of a yard-stick 15 or other pole adapted for the purpose in view, whereby said boxes may be brought down from their shelves or replaced thereon, as desirable.

Other objects and advantages of the invention will appear in the following description, and the novel features thereof will be particularly pointed out in the claims.

Referring to the drawings, Figure 1 is a perspective of one end of a box provided with 20 a socket constructed in accordance with my invention. Fig. 2 is a similar view of a modification. Fig. 3 is a similar view of another modification. Fig. 4 is a plan of the blank for constructing the form shown in Fig. 1, 25 and likewise Figs. 5 and 6 are plans of the blanks for the construction of sockets shown in Figs. 2 and 3. Fig. 7 is a modification of the securing means.

Like numerals of reference indicate like 30 parts in all the figures of the drawings.

Referring particularly to Figs. 1 and 4, 1 represents a box of any ordinary construction, and preferably of that kind used upon shelves 35 of stores, and to the exposed end of the same 45 there is secured a socket 2, in this instance formed of sheet metal, and projecting from and preferably integral with a securing-plate 3, in this instance secured to the box by means of spurs struck from the metal and passed 50 through the wall of the box and clinched, said plate also serving as a guard for the end of the box, whereby the engaging end of the

stick in coming in contact therewith in the act of entering the socket is prevented from scraping or otherwise injuring or defacing the 55 box.

Although I have herein described my invention as formed of sheet metal, it is apparent that the same may be formed of any suitable fabric or pasteboard, leather, or other 60 material, and in any manner desired. I have herein, however, illustrated and described a few of what I consider my most practical forms.

In Fig. 4 the blank is of oblong shape and 65 a transverse fold-line 4 is made at approximately the center of the same and a second parallel fold-line 5 a short distance from the first-mentioned line, and longitudinal fold-lines 6, parallel to each other, extend from the 70 fold-line 4 to the lower end of the blank. Rectangular portions of the blank are now removed at each side of the same, said portions being bounded by the longitudinal edges and the parallel and oppositely-disposed 75 fold-lines 4, 5, and 6. This leaves the plain half of the blank intact and with four rectangular corners. In each of these corners I provide divergent slits or cuts 7, leaving outer 80 acutely-shaped tongues 8, which are struck down at a right angle to the blank and form a means for attaching the securing-plate 3 to the box. The blank is now folded upon the lines 4 and 5 and is severed from the fold-lines 6 to 6 near its end and upon divergent 85 lines extending from the lines 6 to the outer corners of the blank. After folding upon the lines 4 and 5 the blank is folded upon the lines 6, so that the opposite flaps 9, formed by the fold, may be soldered at their edges to 90 the face of the securing-plate 3, and the ends beyond the edge of the blank are flared or divergent, so as to form guides and facilitate the introduction of the end of a yard or other stick 10.

In Fig. 2 essentially the same blank is employed, with the exception that in lieu of forming the opposite square recesses a diagonal cut is made from the point where the lines 6 join the line 4 to the outer corners of the blank. The blank is then folded upon the line 4, only the line 5 being omitted, and the inclined edge of the wing 9 is soldered to the securing-plate so that the socket formed by 95 100

the blank is contracted toward its upper end, and therefore adapted to receive a stick or pole the end of which is somewhat reduced or chamfered. This form of blank, previous 5 to folding, is shown in Fig. 5.

In Fig. 6 the construction is varied by simply slitting the blank upon the lines 4 and 5 from the lines 6 outwardly and bending the intermediate portions upwardly to form sides, 10 the flaps 9 being bent over the sides and secured to their edges to the securing-plate. The product of this blank is clearly shown in Fig. 3.

In Fig. 7 I have illustrated a means for securing the securing-plate to the wall of the box, and the same consists in providing the edge of the securing-plate 3 with a hinged pin 12, adapted to be passed through the wall of the box and to engage at its free end a catch 20 13, formed at the opposite end of the plate and passed through the wall of the box.

Having thus described my invention, what I claim is—

1. The herein-described box-lifter, the same 25 comprising a flat securing-plate and an inverted socket located at the upper end of the same, so as to leave a portion of the plate below the socket, and having top, front, and opposite side walls, the socket and plate being formed of sheet metal, substantially as specified.

2. The herein-described box-lifter, the same 30 comprising a securing-plate and an inverted socket located at the upper end of the same, said socket having top, front, and opposite side walls, the plate extending below the socket to form a guard-plate, the socket and plate being integral and struck up from a blank of sheet metal, substantially as specified.

3. The herein-described box-lifter, consisting of a sheet-metal securing-plate rectangular in plan and having V-slits at its four corners or angles, the metal intermediate said slits being bent to form securing-tongues, and 45 an inverted socket located at the upper end of the plate, the socket and plate being integral and struck up from a single blank, substantially as specified.

4. A box provided with a lift consisting of 50 an inverted socket and a sheet metal securing-plate extended below the socket to form a guard-plate, and having spurs struck up from the plate, inserted through the wall of the box, and clinched thereover, substantially 55 as specified.

5. The herein-described lift adapted to be secured to the wall of a box, comprising a metallic securing-plate having integral struck-up spurs at its corners, and having an inverted socket located at its upper end, the side walls of the socket being flared or oppositely inclined and terminating below the socket to form guides, substantially as specified. 60

6. The herein-described blank folded upon the transverse parallel lines 4 5 and the longitudinally-disposed lines 6, extending from the line 4 to the edge of the blank, said blank being scored from the lines 6 to the outer 70 edges of the blank and having its corners scored, as at 7, forming spurs 8, substantially as specified.

In testimony that I claim the foregoing as my own I have hereto affixed my signature 75 in presence of two witnesses.

FRANKLIN PHILIP MORRISON.
